COMBINED ROOM DIVIDER AND TWIN BED UNIT

John Schneider, 5748 Bates St., San Diego, Calif.

Filed Mar. 5, 1962, Ser. No. 69,089

Term of patent 14 years

(Cl. D33—19)

Fig. 1

Fig. 2

Fig. 3

Fig. 4

I claim:

The ornamental design for a combined room divider and twin bed unit, as shown.
